UNITED STATES PATENT OFFICE

HERMAN ROSENMAN, OF NEWARK, NEW JERSEY, ASSIGNOR TO LEO ROSEMAN, OF
NEWARK, NEW JERSEY

FASTENER TAPE

Application filed March 18, 1930. Serial No. 436,669.

This invention relates in general to fastener tape which includes a strip or strips of fabric having secured thereto hook fastener elements, and more particularly the invention is directed toward the formation of such tapes with novel and improved means to serve as a resilient lock or mousing for the hooks to hold eyes cooperating with the hooks against accidental disconnection from the corresponding hooks, such means being intended to replace the ordinary integral resilient wire mousing or "hump" commonly used in hook fastener elements for the same purpose.

Another object of the invention is to provide a common means for securing a hook fastener element to a garment or fastener tape and to serve as a resiliently releasing mousing for the hook.

Other objects are to provide a fastener tape in which the hook fastener elements are secured thereto by any means, including stitching, which also serves the purpose of a resilient mousing for the hook to prevent accidental disconnection of an eye from the hook; to provide a fastener tape wherein the stitches for securing the base of the hook to the tape are so constructed and arranged as to serve as a resilient lock or mousing for the hook; to provide such a construction which by elimination of the usual integral wire "hump" from the hook enables the hook to be made with less wire so as to save a minimum of approximately thirty-three per cent of wire and thereby reduce the cost of the fastener tape, and to obtain other advantages and results as will be brought out by the following description.

Referring to the accompanying drawings in which corresponding and like parts are designated throughout the several views by the same reference characters,

Figure 1 is a fragmentary top plan view of the fastener tape embodying my invention, showing the fabric folded and with a fastener hook blank inserted in the fabric and stitched thereto.

Figure 2 is a horizontal sectional view on the line 2-2 of Figure 1.

Figure 3 is a longitudinal vertical sectional view on the line 3-3 of Figure 1, showing the bill of the hook completed.

Figure 4 is a top plan view of the fastener tape showing the hook completed.

Figure 5 is a view similar to Figure 1 showing a modification of the invention, portions being broken away and shown in section for clearness in illustration.

Figure 6 is a transverse vertical sectional view on the line 6-6 of Figure 5.

Figure 7 is a longitudinal vertical sectional view on the line 7-7 of Figure 5 with the hook completed.

Figure 8 is a top plan view of a modified form of fastener tape embodying my invention.

Figures 9 and 10 are transverse vertical sectional views on the lines 9-9 and 10-10 of Figure 8, and

Figure 11 is a perspective view of the fastener shown in Figure 8 with the hook completed.

Specifically describing the embodiment of the invention described in Figures 1 to 4, inclusive, the fastener tape includes a strip of suitable material such as cotton fabric, having a main portion 1 and one edge portion folded inwardly at 2 upon said main portion to form a second ply 3 which is again folded outwardly at 4 to form another ply 5. The other edge portion is folded inwardly over the main portion at 6 to form a ply 7 and is then folded outwardly at 8 to form another ply 9. The folds 4 and 8 are provided at spaced points with corresponding perforations, slits, openings or pierced holes 10 through which are inserted or in which are formed hook fastener elements 11 with the base portions 13 disposed between the plies 3 and 5. These base portions are substantially loops having arms 131 at substantially right angles to the bill portions 130. In making the fastener tape the hooks may be applied to the tape in any suitable manner. For example the hooks may be formed substantially flat as shown in Figure 1 and inserted through the openings 10, and after the base portions of the hooks have been mounted on

the fastener tapes, the bills 130 of the hooks 100

are bent upwardly over the base portions as shown in Figure 4 of the drawings. As described and claimed in an application of Leo Roseman for United States Letters Patent, 5 this operation may be accomplished in any suitable way and by any apparatus which will bend the bills of the hooks as described.

The hooks are secured to the tape by a line of stitching 14 which extends longitudinally

- 10 of the strip and which is interrupted at each hook to pass laterally of the strip over arms 131 of the base portions of the hook as shown at 15 and as is known to those skilled in the art. In accordance with the invention 15 two offset or lateral stitches 15 and 150 are utilized at each side of each hook and the stitches 15 which pass over the bases of the hooks are superposed and plural or greater in number than usual so that they form a 20 projection above the surface of the ply 5. The bases and bills of the hooks thus are in such relation that the stitches 15 are located substantially beneath the bills or ends of the hooks adjacent the outer ends thereof, so as 25 to provide a seat, clearance or nest for an eye fastener element between the mousing stitches 15 and the bend in the hook. These stitches 15 thus form protuberances or projections extending toward the bill of the hook when the latter is bent into finished relation to the base 12 as shown in Figures 3 and 4, so that the space between the stitches and the bill of the hook is normally less than the thickness of the wire of the cooperating eye fastener 30 element. At the same time that the bill 130 is so bent, the flap 9 is folded inwardly at 16. This flap then covers the stitches 15, but the stitches hold the flap in close relation to the overlying bill 130 of the hook, as clearly 35 shown in Figure 3 so that the protuberances thus formed serve as a resilient mousing for the hook and accomplish the same purpose as the integral wire hump on known fastener hooks. The tape may be secured to a garment 40 30 in any known manner as by stitches 31 and 32, as shown in Figure 4.

A slight modification of the invention is shown in Figures 8 to 11 inclusive, in which the fastener tape is of a different construction, including a strip B of fabric having one edge folded inwardly to form a ply 17 and the other edge folded inwardly at 18 and returned at 19 to form two other plies overlying the ply 17. The hook 20 is identical in 55 construction with the hook shown in Figure 1 and is arranged between the overlying plies 19 and 17, and the hook is secured to the tape by a line of stitching 21 which is offset to form stitches 220 and 22 the latter of which 60 overlie the base of the hook just as do the stitches 15. After the stitches have been so formed the bill of the hook is bent into finished position, indicated at 23 in Figures 9 to 11 inclusive. In this form of the invention, 65 the stitches 22 are multiplied just as are the

stitches 15, and they remain exposed beneath the bill of the hook so as to form protuberances or projections to act as a mousing for the hook as clearly shown in Figures 9 and 10.

Another modification is shown in Figures 5 to 7 inclusive wherein the fabric tape is substantially identical with that shown in Figure 1. In this form of the invention, after the hook blank 24 has been inserted through the slits or openings in the tape, a cord or the like 25 is laid over the base portions 26 of the hooks, longitudinally of the strip, between the plies 3 and 5 adjacent the fold 4. This cord may be secured in position in any suitable manner, but preferably is secured by the lateral or offset stitches 27 corresponding to the stitches 15 in Figure 1 of the drawings. If desired, an additional longitudinal line of stitching 28 may be provided closely adjacent to the cord, and passing through the plies 3, 5 and 1. With this construction the lateral stitches 27 need not be multiplied but may be as known in the art, and the protuberance to serve as a mousing for the hook is formed by the pad 25, as clearly shown in Figures 6 and 7, beneath the bill 29.

Instead of inserting the hooks into the tape in flat condition and bending the bills as above described after the hooks are sewed to the tape, I may perform the sewing operation after the hooks are completed.

It will be observed that the mousings of the hooks have uniform resiliency which is practically impossible to attain with known hooks having wire "humps" because of differences in the resiliency of the wire, inaccurate bending of the wire and relative displacement of the bills of the hooks and the humps caused by handling and otherwise.

It should be understood that the forms of the invention herein illustrated and described, while now preferred are primarily for the purpose of illustrating the principles of the invention and that many modifications and changes may be made in the details of 105 construction of the fastener tape, and in the construction of the mousing, without departing from the spirit or scope of the invention. Also, the invention is not limited to use in fastener tapes but may be embodied 110 in fastener elements directly applied to garments or the like.

Having thus described my invention, what I claim is:

1. A fastener tape comprising a strip of fabric, hook fastener elements on said strip having bills and bases, a cord extending across said bases beneath said bills, and means for securing said cord on said strip so as to form mousings for said fastener elements.
2. The combination of a piece of fabric, a plurality of hook fastener elements each having a base and a bill overlying said base, and a continuous line of stitching on said fabric and laterally offset at opposite sides of each

of said fasteners to overlie said base for securing said fastener element to said fabric, certain of the laterally offset stitches being beneath said bill adjacent the outer end thereof and being plural and superposed to form collectively a protuberance spaced from the bill a distance less than the thickness of an eye to cooperate with said hook to serve as a mousing.

3. The combination of a strip of fabric, a plurality of hook fastener elements each having a base and a bill overlying said base, the base having oppositely extending arms each at substantially right angles to the bill at one side thereof, a line of stitching running longitudinally of said strip and laterally offset at opposite sides of each fastener element closely adjacent the bill thereof to overlie said arms of the bases, certain of the lateral 20 stitches being beneath said bill adjacent the outer end thereof and plural and superposed to form collectively a protuberance spaced from said bill a distance less than the thickness of an eye to cooperate with said hook.

4. A fastener tape comprising a strip of fabric, a humpless hook on said strip having a base and a bill in overlying spaced relation to said base, and a continuous line of stitching running longitudinally of said strip and laterally offset at opposite sides of said hook to overlie said base for securing said hook to said fabric, said offset stitches being beneath said bill and plural and superposed to form collectively a protuberance spaced from said bill a distance less than the thickness of an eye to cooperate with said hook to serve as a mousing.

HERMAN ROSENMAN.
